UNITED STATES PATENT OFFICE.

GEORGE W. PRINCE, OF CLEMENCEAU, ARIZONA, AND ARCHIBALD DOUGLAS, OF NEW YORK, N. Y., ASSIGNEES TO UNITED VERDE EXTENSION MINING COMPANY, OF NEW YORK, N. Y., A CORPORATION OF DELAWARE.

SMELTING FURNACE AND THE METHOD OF SMELTING ORES THEREIN.

Application filed June 9, 1925. Serial No. 35,862.

To all whom it may concern:

Be it known that we, GEORGE W. PRINCE and ARCHIBALD DOUGLAS, citizens of the United States, and residents, respectively, of 5 Clemenceau, in the county of Yavapai and State of Arizona, and of the borough of Manhattan, in the city and State of New York, have invented a new and useful Improvement in Smelting Furnaces and the 10 Method of Smelting Ores Therein, of which the following is a specification.

The object of this invention is to provide novel means for and method of feeding ores into a reverberatory furnace whereby a more 15 rapid and effective smelting of the ores as well as great economy in fuel is obtained by depositing the ores on the floor of the furnace to form a continuous longitudinal mound with its apex spaced from the unfettled side walls of the furnace, the sides 20 of the mound sloping to the said side walls of the furnace, to form valleys for the flow of the molten material along the side walls.

A further object is to provide means for 25 feeding the ores into the furnace substantially continuously, so that the continuous longitudinal mound will be maintained during the smelting operation and thereby the most effective and economical smelting of 30 the ores may be obtained.

In the accompanying drawings:

Fig. 1 represents a reverberatory furnace in horizontal section with the improvements incorporated therein.

Fig. 2 represents a longitudinal vertical section through the furnace, taken in the plane of the line II--II, of Fig. 1.

Fig. 3 represents a transverse vertical section through the furnace taken in the plane 40 of the line III--III, of Fig. 2.

The furnace floor is represented by 1, the arched roof by 2 and the unfettled side walls by 3, 4. This furnace may be provided at its firing end with the usual nozzles 5, for introduction of the heating medium, and its other end with the usual flue 6.

In the present instance where a single longitudinal mound of ore is to be formed, and maintained on the floor of the furnace, 50 the roof 2 is provided centrally with a longitudinal row of closely spaced passages 7 through which the ores are fed in from aed choppers 8 communicating with a suitable feeding mechanism 9, in such a manner

that the continuous longitudinal mound of 55 ores is formed and maintained with the apex of the mound spaced from the side walls 3 and 4 of the furnace, thereby producing valleys between the sloping sides of the mound and the side walls of the furnace, 60 along which valleys the molten material flows to the flue end of the furnace.

It is intended that this feeding of the ores shall be substantially continuous so that the continuous longitudinal mound will be maintained at the proper height to utilize the effect of the heating medium most economically and at the same time to present a very extended ore surface to the action of said heating medium. This substantially continuous feeding in of the ores, as distinguished from periodic feeding in, permits the ores to be submitted to the action of the heating medium at a time when the ores most readily absorb the heat of the heating 75 medium.

If found necessary, a greater or lesser portion of each of the side walls may be made of non-cerrosive material such, for instance, as magnesite or chrome bricks 10, where the molten material comes into contact with the said side walls.

What we claim is:

1. The method of smelting ores in reverberatory furnaces which consists in substantially continuously feeding the ores into the furnace chamber in such a manner that a continuous longitudinal mound is formed and maintained with its apex spaced from the side walls of the furnace chamber, and subjecting the mound to the action of a heating medium.

2. The method of smelting ores in reverberatory furnaces which consists in feeding the ores into the furnace chamber in such a manner that a continuous longitudinal mound is formed with its apex spaced from and its sloping sides leading to the side walls of the furnace chamber, and subjecting the mound to the action of a heating medium.

3. The method of smelting ores in reverberatory furnaces which consists in substantially continuously feeding the ores into the furnace chamber in such a manner that a continuous longitudinal mound is formed and maintained with its apex spaced from and its sloping sides leading to the side

walls of the furnace chamber, and subjecting the mound to the action of a heating medium.

4. In a reverberatory furnace, means for feeding the ores into the furnace chamber to form a continuous longitudinal mound with its apex spaced from the side walls of the furnace chamber, and means for subjecting the mound to the action of a heating medium.

5. In a reverberatory furnace, means for feeding the ores into the furnace chamber to form a continuous longitudinal mound with its apex spaced from and its sloping sides leading to the side walls of the furnace chamber, and means for subjecting the mound to the action of a heating medium.

6. In a reverberatory furnace, means for substantially continuously feeding the ores into the furnace chamber to form and maintain a continuous longitudinal mound with its apex spaced from and its sloping sides leading to the side walls of the furnace chamber, and means for subjecting the mound to the action of a heating medium.

7. In a reverberatory furnace, means for feeding the ores into the furnace chamber to form a continuous longitudinal mound with its apex spaced from and its sloping sides leading to the side walls of the furnace chamber to produce valleys for the flow of the molten material along the said side walls, portions of said side walls being formed of a non-corrosive material, and means for subjecting the mound to the action of a heating medium.

8. In a reverberatory furnace, means for feeding the ores into the furnace chamber to form a continuous longitudinal mound with its apex spaced from and its sloping sides leading to the side walls of the furnace chamber to produce valleys for the flow of the molten material along the said side walls, portions of said side walls which come in contact with the molten material being formed of a non-corrosive material, and means for subjecting the mound to the action of a heating medium.

9. A reverberatory furnace having a plurality of passages opening through its roof into the furnace chamber at a predetermined distance from the side walls thereof, means for substantially continuously feeding the ores through said passages by gravity into the furnace chamber to form a continuous

longitudinal mound with its apex spaced from the said side walls, and means for subjecting the mound to the action of a heating medium.

10. A reverberatory furnace having unfettled side walls, means for feeding the ores into the furnace chamber to form a continuous longitudinal mound with its apex spaced from the side walls, and means for subjecting the mound to the action of a heating medium.

11. A reverberatory furnace having unfettled side walls, means for substantially continuously feeding the ores into the furnace chamber to form a continuous longitudinal mound with its apex spaced from the side walls, and means for subjecting the mound to the action of a heating medium.

12. A reverberatory furnace having unfettled side walls and also having passages opening through its roof into the furnace chamber at a predetermined distance from the side walls, means for feeding the ores through said passages into the furnace chamber to form a continuous longitudinal mound with its apex spaced from the said side walls, and means for subjecting the mound to the action of a heating medium.

13. A reverberatory furnace having unfettled side walls and also having passages opening through its roof into the furnace chamber at a predetermined distance from the side walls, means for substantially continuously feeding the ores through said passages into the furnace chamber to form a continuous longitudinal mound with its apex spaced from the said side walls, and means for subjecting the mound to the action of a heating medium.

14. A reverberatory furnace having unfettled side walls, means for feeding the ores into the furnace chamber to form a continuous longitudinal mound with its apex spaced from the side walls, and means for subjecting the mound to the action of a heating medium, the portions of the said walls which are exposed to the molten material being of non-corrosive material.

In testimony, that we claim the foregoing as our joint invention, we have signed our names this 21 day of May, 1925, and this 15th day of May, 1925.

GEORGE W. PRINCE,
ARCHIBALD DOUGLAS.
